UNITED STATES PATENT OFFICE.

WILLIAM J. HEARN, OF NEW YORK, N. Y.

PUMP.

SPECIFICATION forming part of Letters Patent No. 436,708, dated September 16, 1890.

Application filed March 6, 1890. Serial No. 342,844. (No model.)

To all whom it may concern:

Be it known that I, WILLIAM J. HEARN, a citizen of the United States, residing at New York, in the county and State of New York, 5 have invented new and useful Improvements in Pumps, of which the following is a specification.

This invention relates to an improvement in pumps; and the invention consists in the 10 details of construction set forth in the following specification and claims and illustrated in the accompanying drawings, in which—

Figure 1 is a sectional elevation of a pump, 15 the section being taken along line *x x*, Fig. 2. Fig. 2 is a section along line *y y*, Fig. 1. Fig. 3 is a section along line *z z*, Fig. 1. Fig. 4 is a section along line *w w*, Fig. 2.

In the drawings, the letter *A* indicates a barrel in which works a piston *B*. The piston-rod *C* communicates with an actuator, such as a lever *D*. The descent of the piston *B* allows water or liquid to pass through the upwardly-opening valve *X* of the piston, and the ascent 25 of such piston closes the valve *X* and forces the liquid which has collected above the piston *B* out through the discharge-opening *E*. The barrel *A* communicates by means of a pipe *F* with a vessel or chamber *G*. In the chamber *G* rises a tube or pipe *H* for a certain 30 distance, and said tube *H* communicates with a lower chamber *I*. From the lower chamber *I* a pipe or tube *K* leads to the fluid which is to be pumped. The tube *K* is provided with 35 an upwardly-opening valve *L*.

A cup *T* sits snugly over the pipe *H*, and said cup can slide on said pipe. A spring *V* tends to force the cup *T* upward. Said cup has an upwardly-opening valve *U*. This 40 valve *U* is shown in form of a flat valve; but any suitable valve—such as a ball-valve—may be substituted.

In the lower chamber *I* moves a piston *W*, having a valve *Y*. The rod *O* of the piston 45 is guided near its upper end by passing through the upper part of the cup *T* and through the valve *U*. The valve *U* is ca-

pable of a certain motion independent of the cup *T*. A nut *M* prevents the valve coming off the rod *O*.

When the piston *B* is forced down, the cup *T* and piston *W* descend, opening the valves *U* *Y* and closing valve *L*. Water or fluid in the lower part of chamber *I* thus passes through valve *Y* to the upper part of chamber *I*, and fluid in the cup *T* passes through valve *U* into chamber *G*. The ascent of piston *B* causes the fluid to pass from chamber *G* through pipe *F* into barrel *A*, while at the same time the spring *V* raises the cup *T* and piston *W* so as to close valves *U* *Y* and open valve *L*. Fluid then passes from pipe *K* into the lower chamber *I* to replace the fluid which passes from chamber *I* into pipe *H* on the rise of piston *W*.

The pumping mechanism shown in the drawings is in form of a hand-pump; but of course a steam-pump or any suitable pump mechanism can be used.

By connecting the chambers *G* *I* with their 70 contained parts to the pumping mechanism, said mechanism is assisted so that the fluid can be raised to a greater height than could be obtained by the unaided pumping mechanism.

What I claim as new, and desire to secure by Letters Patent, is—

1. The combination, with the pump-barrel *A* and piston *B*, of the upper chamber *G*, the lower chamber *I*, the pipe *F*, connecting the 80 top of the upper chamber with the pump-barrel, the pipe *H*, rising in the upper chamber, the valved cup *T*, rising and falling on the pipe in the lower chamber, a spring *V*, surrounding the pipe and cup within the upper chamber and bearing against the cup to elevate the same, a valved piston *W* in the lower chamber, the piston-rod *O*, and valved tube *K*, substantially as described.

2. The combination, with a pumping mech- 90 anism, of the upper chamber having its top end connected with the pumping mechanism, the lower chamber connected to the upper chamber, the pipe rising from the lower cham-

ber, the cup moving vertically on the pipe in the upper chamber, the spring surrounding the pipe and cup within the upper chamber and bearing against the cup to raise the 5 same, a valved piston in the lower chamber, a piston-rod extending through the upper end of the cup, a valve rising and falling on and guided by the piston-rod above the cup and seating on the latter, and a valved tube lead-

ing from the lower chamber, substantially as described.

In testimony whereof I have hereunto set my hand in the presence of two subscribing witnesses.

WILLIAM J. HEARN.
